(57) **CLAIM**

The ornamental design for a disabled vehicle indicator as shown and described.

DESCRIPTION

FIG. 1 is an isometric view of a disabled vehicle indicator showing my new design;

FIG. 2 is a front elevational view thereof;

FIG. 3 is a rear elevational view thereof;

FIG. 4 is a right elevational view thereof, a left elevational view is a mirror view of right elevational view; and,

FIG. 5 is a top plan view thereof, a top plan view is a mirror view of the bottom plan view.

The broken lines in the drawings illustrate portions of the disabled vehicle indicator that form no part of the claimed design.

In the drawings, the broken lines depict stitching, a claimed feature of the design.
